[57] CLAIM

The ornamental design for a figurine, as shown and described.

DESCRIPTION

FIG. 1 is a front elevational view of a figurine showing my new design;

FIG. 2 is a rear elevational view showing the design for the figurine of FIG. 1;

FIG. 3 is a left side elevational view showing the design for the figurine of FIG. 1;

FIG. 4 is a right side elevational view showing the design for the figurine of FIG. 1; and,

FIG. 5 is a top elevational view showing the design for the figurine of FIG. 1.

In FIGS. 1-5, the broken lines showing of the basketball jersey, the shoes, and the pedestal on which the figurine is supported is for illustrative purposes only and forms no part of the claimed design.
